CONTAINER

Jesse T. Chapman, Sikeston, Mo., assignor of two-fifths to Frederick H. Cole, Sikeston, Mo.

Application April 15, 1937, Serial No. 136,963

1 Claim. (Cl. 229—51)

My invention relates generally to improvements in containers and more particularly to improvements in containers for individually packaging and dispensing ice cream and other confections.

Ice cream is now packaged and sold in various kinds of individual containers such as the well known small paper cups but all of these packages have a number of disadvantages chief of which is their relatively great expense, making it necessary for the producer to cheapen his product in order to sell it at a fair profit. All these conventional packages are unsanitary in one way or another and are hard to handle and to store in a refrigerator without taking up a great deal of room and still, by their shape, leaving a considerable lost air space between and around them.

It is the main object of my invention to provide a container which will have none of these disadvantages and which will be extremely inexpensive to manufacture, easy to pack, sanitary and convenient.

Another object is to provide a container which is folded up from a single blank of material to form an elongated sack-like element to receive the ice cream and with its sides perforated some distance so that they may be peeled down away from the cream as it is eaten, it being evident that the cream may be eaten in this manner without the hands ever coming in contact with it.

Another object is to provide a container of this elongated sack-like form closed at its lower end and with sealing flaps at upper end which may be folded over on themselves to seal the container, the said perforations running down the sides of the container from the junctions of these flaps so that the customer by loosening the flaps and then pulling on them as required may peel away the sides from the cream as he eats.

Another object is to provide a container of this kind in which the blank from which it is formed is so shaped that the container when filled is substantially square at its upper end portion but tapers off and is relatively flat at its lower end. The aforesaid perforations are then run down the "corners" of the container and are terminated some distance from the lower end. This shape and arrangement is of great importance in that the four sides thus formed at the upper portion of the container may be readily peeled back as required in the eating of the cream and then, when the limit of the perforations is reached, the remainder of the cream in the bottom may be readily pushed up and eaten by simply squeezing the flat tapered lower end of the container. Another advantage arising from this shape of the con-

tainer is the ease with which a number may be packed or stored. For example, the containers may be laid flatwise or side by side in a box of such width as to just accommodate the length of the containers whereupon the said flaps will be held closed and will require no actual sealing. In this arrangement it will also be evident that there will be no wasted air space in and around the containers thus effecting a saving of refrigeration space to the storekeeper.

10

With these and other objects in view the invention resides in the novel construction and arrangement of parts as hereinafter fully set forth and claimed, reference being had to the accompanying drawing as showing a preferred embodiment of my invention for purposes of exemplification.

In the drawing:

Figure 1 is a perspective view of my container as filled and sealed.

20

Figure 2 is an edge view of my container.

Figure 3 is a perspective view of the container showing two sides peeled off as they would be in eating the ice cream from the container.

Figure 4 is a plan view of the blank from which the container is formed.

In carrying out my invention I provide a blank 5 of waxed, paraffined or otherwise waterproofed paper, cardboard or other suitable material. This blank is cut to a substantially rectilinear shape 30 with a straight lower end or edge 6 and upper end or edge 7 which run parallel with each other and are joined by the lateral margins or sides 8—9 tapering downwardly so that the blank is narrower at its lower end as shown. The body 35 of the blank is divided by the fold lines 10—11—12 into four panels or sections and the aforesaid upper end 7 has three equally spaced corners or indentations 13 cut down all to an equal distance which arrangement forms four flaps or tabs 14 40 at the upper end. The outermost flaps also have their outer edges cut off angularly down toward the upper corners of the blank so that all the flaps have the same upwardly tapering shape. The center fold line 10 terminates some distance short of the lower end of the blank as shown whereas the outer lines 11—12 run to the lower end, and, the aforesaid indentations 13 being located at the upper ends of these fold lines, the flaps thus form extensions of the four panels 50 defined by the lines. The upper portions of the outer lines 11—12 as well as the entirety of the center line 10 are defined, and in fact formed by coextensive lines of tiny perforations as indicated by the numeral 16. One side, as 8, of the

blank has a narrow sealing flange or lip 17 extended its entire length while the lower end 6 has a similar flange or lip 18 which however extends and is located only between the outer fold lines 11-12 at the center portion of the blank. The junction between the lip 17 and the blank is defined along its upper portion by a line of small perforations 16a extending down about the same distance as the others 16. It will be noted that the lines 11-12 extend substantially parallel with the adjacent margins 8-9 so that the center of the blank defined by these lines has about the same taper as the blank as a whole. The foregoing completes the blank and it will be apparent that, in this flat form, a great number of the blanks may be readily and compactly packaged, shipped and stored.

In forming up the container from the blank the lateral portions or panels defined by the lines 11-12 are folded over on the center of the blank so that the lip 17 overlies the margin 8 to which the lip is then sealed or fastened in any well known manner. The lower lip 18 is then turned up and over the adjacent lower margins of these folded panels and similarly secured thereto. In this manner a flat sack or bag is formed closed at the bottom and all sides but open at the upper end so that it may be readily filled with ice cream or any desired confection. The containers may be shipped and stored in this form also. When the container is filled it of course expands and the upper portion assumes a square shape the corners 19 of which are defined by the lines 16-16a of perforations and the contiguous sides 20 of which are formed by the four panels set out by the fold lines 10-11-12 aforesaid. Due however to the tapering shape of the blank 5 as a whole and the termination of the perforations 16-16a above the lower end of the blank the lower portion of the container assumes a relatively flat and downwardly tapering shape as indicated at 21 which blends nicely into the square shape of the upper portion. It will be noted also that the taper of the blank results in the finished container being of equal width throughout its length as viewed from the front or back (Figure 1) facilitating its storage and packing. When filled the flaps 14 are folded over on each other in any order and sealed thus closing the upper end of the container and protecting the contents. Then to eat the cream the customer loosens the

flaps, pulls them upwardly and outwardly and peels the sides 20 down exposing the cream, the sides being peeled further as necessary until the limit of the perforations is reached. Of course these perforations tear readily as the sides are peeled. During the time that the upper portion of the cream is being eaten the heat of the hand holding the lower end of the container will have softened the cream at the lower end and this may then be readily forced up as required by 10 simply squeezing the flat bottom of the container.

It will be apparent from the foregoing that the whole operation of eating from this container may be carried out without the use of a spoon and without the hands ever coming in contact with the food and the container is thus both sanitary and convenient. Since but a single piece of material is used for each container and it is of such shape that there will be very little waste material in cutting, this form of container is 20 extremely inexpensive enabling the producer to realize a fair profit even on the smallest individual sales and without cheapening his product.

In storing the containers in the refrigerator they may be laid side by side and due to their 25 elongated shape they will pack nicely and leave very little waste air space.

The containers of course may be made in any desired sizes and of any suitable material.

While I have herein set forth a certain preferred embodiment of my invention it is understood that I may vary from the same in minor structural details so as best to provide a practical device for the purposes intended, not departing from the spirit of the invention and within the scope of the appended claim.

I claim:

A container of flexible material and of an elongated, sacklike formation, square at its upper end portion and gradually tapered downward to a flat, wedge like form with the lower edge disposed diagonally relative to the squared upper portion, the said lower end being closed, spaced closure flaps extended marginally at the upper end of the container, one from each side of the squared, upper portion thereof, and lines of perforation extended medially along the lower tapered sides of the wedge like portion and merging into the corners of the upper, squared portion.

JESSE T. CHAPMAN.
